(57) **CLAIM**

The ornamental design for an edge-lit fin assembly, as shown and described.

DESCRIPTION

FIG. 1 is a front perspective view of an edge-lit fin assembly showing the new design;

FIG. 2 is a left elevational view thereof, a right elevational view being a mirror image thereof;

FIG. 3 is a back elevational view thereof;

FIG. 4 is a front elevational view thereof;

FIG. 5 is a top plan view thereof;

FIG. 6 is a bottom plan view thereof;

FIG. 7 is a rear perspective view thereof; and,

FIG. 8 is an exploded front perspective view thereof.

The broken lines showing environment in the drawings are included for illustrative purposes only and form no part of the claimed design.
